UNITED STATES PATENT OFFICE

JOHN W. ALDERSON, OF SAN FRANCISCO, CALIFORNIA.

EYE-SHADE.

No. 876,676.

Specification of Letters Patent.

Patented Jan. 14, 1908.

Application filed May 8, 1907. Serial No. 372,499

To all whom it may concern:

Be it known that I, JOHN W. ALDERSON, citizen of the United States, residing in the city and county of San Francisco and State 5 of California, have invented new and useful Improvements in Eye-Shades, of which the following is a specification.

My invention relates to eye-shades.

Its object is to provide a neat, attractive 10 eye-shade which can be carried in the pocket if desired, which can be quickly and accurately adjusted to fit any head, and which especially is arranged to intercept all vertical or horizontal rays of light, whether the 15 light is overhead, in front, or at either side of the eyes.

The invention consists of the parts and the construction and combination of parts as hereinafter more fully described and 20 claimed, having reference to the accompanying drawings, in which—

Figure 1 is a perspective view of the device. Fig. 2 is a front view; and Fig. 3 is a side view.

25 The invention comprehends essentially two eye-shade members A, which are so constructed as to fit the brow snug over the eyes and extend forward and downward across the normal line of vision, and also to extend 30 around the temples at the sides of the eyes in such fashion, as to protect the eyes from all overhead lights as well as from front and side lights.

In the preferred form of construction of 35 the eye-shade members, they are essentially spherical; that is, in the form of spherical segments with their convexities presented upwardly over the eyes, with the pointed side extensions a arranged to extend around the 40 side of the face and to bear against the temples. These eye-shade members may be made of any suitable material which will exclude or modify the rays of light. As a rule I prefer to make them of either metal 45 or celluloid. The shade-members are preferably provided each with a peripheral flange or bead 2 for the purpose of giving strength and stiffness to them. The eye-shade members may be made integral, or as here shown, 50 they are preferably made separate and connected by a bridge-piece 3, which latter may or may not be adjustable. Preferably the bridge-piece is adjustable as here shown, in which the bridge has the bent ends 4 provided 55 with the slots 5 which receive the locking

screws 6 in the little brackets 7 which are fixed to each eye-shade member.

By making the nose-piece or bridge-piece vertically and horizontally adjustable in this manner, the eye-shade can be raised or lowered, or moved to or from the face so as to effect a perfect adjustment of the eye-shade to faces or heads of different contours.

Any suitable means may be employed to hold the eye-shade on the head. In the 60 present instance there are shown the bows 8 pivoted to the lower edges of the eye-shade members and foldable to swing inward into a small compass. The spherical or dish-shape construction of the eye-shade members, permits the device to be worn in conjunction with ordinary eye glasses.

Having thus described my invention, what I claim and desire to secure by Letters Patent, is—

1. An eye shade comprising a pair of shade members, each of said members being fashioned in the form of a spherical segment having an upper edge in the form of a reverse curve whereby said edge will fit the brow 80 over the eye and extend down at the side of the eye along the temple, and an adjustable nose piece connecting said members at a point below said upper edge.

2. An eye-shade comprising two eye-shade members, each in the form of a spherical segment and having a reversely curved edge to enable the member to extend over the eye and downward in front thereof and to the sides of the eyes for the purpose of protecting 90 the eyes from horizontal as well as vertical rays.

3. An eye-shade comprising two eye-shade members, each in the form of a spherical segment to extend over the eye and downward 95 in front thereof and to the sides of the eyes for the purpose of protecting the eyes from horizontal as well as vertical rays, said nose-piece forming a connection between the shade members at a point below the top 100 edges of the latter, said nose piece being vertically and horizontally adjustable.

In testimony whereof I have hereunto set my hand in presence of two subscribing witnesses.

JOHN W. ALDERSON.
